UNITED STATES PATENT OFFICE

FREDRICH C. LOCHNER, OF NORWOOD, OHIO

STUDY TABLE

Application filed October 25, 1927. Serial No. 223,642.

My invention relates to study tables and more specifically to a concealed compartment and concealed means for pivotally attaching the top thereto.

5 The object of my invention is to provide a study table having a concealed compartment and concealed means for pivotally mounting the top so that when not in use as a study table, it may have the appearance of and be 10 used as an ordinary end table or for similar decorative and useful needs.

A further object of my invention is to provide a study table having a concealed compartment for books, papers, inks, etc., which 15 may be tilted at an angle and used to support one's books when reading.

A still further object is to provide a study table having an adjustable top or cover which can be lifted and swung from over said book 20 compartment, when desired, against the rear side entirely out of the way, or which, when closed, can be tilted and used as a drawing board.

Further objects and advantages will be apparent as the description proceeds.

The invention consists in the construction, combination, location and arrangement of parts, as herein set forth and claimed.

In the drawings:

30 Fig. 1 is an isometric view of the invention as it will appear when in use as an end table;

Fig. 2 is an end elevation of the table with part of the legs broken away and showing one of the locks and disappearing link hinge by dotted lines;

35 Fig. 3 is a similar end view of the opposite end;

Fig. 4 is an isometric view similar to Fig. 1, but showing the top or lid swung upon the link hinges to the rear and resting against the rear lower corner of the compartment and against the standards and the concealed book compartment tilted at an angle to the base of the table legs;

45 Fig. 5 is a vertical section taken on a plane corresponding to line 5—5 of Fig. 4;

Fig. 6 is a section on an enlarged scale on the line 6—6 of Fig. 1, the bolt appearing in elevation; and

50 Fig. 7 is an enlarged view of one of the

locks with a portion of the table appearing in elevation and vertical section;

In the embodiment of my invention as illustrated and which shows a preferred construction, I provide a study table comprising an 55 adjustable top or lid 1, book compartment 2, legs or standards 3 and 4 and brace or stretcher 5, respectively. The compartment 2 comprises ends 6 and 7, sides 8 and 9, bottom 10 and top or lid 1, respectively. Ends 6 and 7, 60 respectively, are provided with suitable locks 11 and 12 (of the chest-lock type) and are pivotally mounted between legs 3 and 4 and held in any desired, tilted or adjusted position by hand screws 13 and pivot bolts 14. 65

Top or lid 1 is attached to ends 6 and 7 by disappearing links 15 and 16, which links are pivotally attached to said ends at 17 and to brackets 18 and 19 on the lid, as clearly shown in Fig. 5. Said ends 6 and 7 are also provided 70 with recesses 20 and 21 and slots 22 and 23, respectively. Said recesses 20 and 21 receive brackets 18 and 19, respectively, of top or lid 1 when said top is in closed position over compartment 2, as shown in Figs. 1, 2 and 3, respectively. 75

Said slots 22 and 23 in ends 6 and 7 receive links 15 and 16 when said lid 1 is in closed position, as before described.

The use of my study table is as follows: 80

Assume that the table is closed, as shown in Fig. 1. When in this position it may be used as an end-table, library table, radio stand, or for many other similar useful purposes.

Should it be desired to put the table in condition for use as a study table, simply unlock locks 11 and 12, lift top or lid 1 off of compartment 2 and swing it backwardly and downwardly to the position shown in Fig. 4. 80 Then, if desired, the book compartment 2 may be tilted by simply loosening hand screws 13, tilting to the desired angle (as shown in Fig. 4, or at any angle) and tightening said screws to hold said compartment 95 in said tilted position.

An advantage of this invention is that a teacher, student, minister, doctor, lawyer, etc., may keep study books, papers, ink, etc., in the compartment 2 convenient for ready 100

reference and when finished with them, the table may be readily closed and used for an end table.

Another advantage of my invention is that 5 the table may be tilted and the top 1 used as a drawing board.

An advantage of my invention is that when 10 the table is not being used as a study table, it may be closed and locked and from all outward appearances be nothing more than an ordinary end table, library table or similar utility table.

It will be understood that certain changes 15 and modifications can be made without departing from the scope or spirit of the invention as defined in the claims.

What I claim as new and desire to secure by Letters Patent is:

1. A study table comprising a tiltably mounted compartment having a vertical slot 20 in each end, an adjustable top for said compartment, standards upon which said compartment is mounted, a link mounted in each of said slots and each link pivoted at one end 25 to said top and at the other end to one end of said compartment whereby when said top is in closed position said links will be concealed within said slots and hold said top from horizontal movement and whereby when said top 30 is moved upon said links to open position said links will move and be guided by said slots to a substantially vertical position and said top will be thrown entirely to the rear of said compartment out of the way of the user.
- 35 2. A study table comprising a tiltably mounted compartment having a vertical slot in each end extending part way therethrough through a portion of its area and extending entirely therethrough through the remainder 40 of its area, an adjustable top for said compartment, standards upon which said compartment is mounted, a link mounted in each of said slots, and each link pivoted at one end to said top and at the other end to one end of 45 said compartment whereby when said top is in closed position said links will extend substantially horizontally within said slots and be concealed therein and whereby when said top is moved upon said links to open position 50 said links will move to substantially vertical position and said top will be thrown entirely to the rear of said compartment with one edge resting against said standards out of the way of the user.
